UNITED STATES PATENT OFFICE.

GEORGE ROBINS, OF JACKSON, MICHIGAN.

HORSESHOE TOE-CALK.

1,144,790.

Specification of Letters Patent. Patented June 29, 1915.

Application filed March 27, 1915. Serial No. 17,488.

To all whom it may concern:

Be it known that I, GEORGE ROBINS, a citizen of the United States, residing at Jackson, in the county of Jackson and State 5 of Michigan, have invented certain new and useful Improvements in Horseshoe Toe-Calks, of which the following is a specification, reference being had to the accompanying drawings.

10 My present invention relates to new and useful improvements in toe calks for horse shoes and as its principal object aims to provide a device of this character which is simple in construction and is so designed 15 that it will be durable in service, being capable of withstanding any strain to which it may be subjected.

20 A further and more specific object of the invention is to provide a toe calk which is accompanied by a holder wherein it is removably seated and by means of which it may be easily and quickly applied to or removed from the toe portion of the shoe.

25 Another object of the invention is to so arrange the holder that it may be readily applied to the shoe, without requiring any material changes in the construction thereof, it being only necessary to drill three threaded bores in the toe portion of the shoe.

30 The above, and other incidental objects of a similar nature, which will be hereinafter more specifically treated are accomplished by such means as are illustrated in the accompanying drawings, described in the following specification, and then more particularly pointed out in the claims which are appended hereto and form part of this application.

With reference to the drawings, wherein 40 there has been illustrated the preferred embodiment of this invention, as it is reduced to practice, and throughout the several views of which similar reference numerals designate corresponding parts, Figure 1 is 45 a bottom face view of the toe portion of a shoe equipped with the improved toe calk; Fig. 2 is a section on the line 2—2, of Fig. 1; Fig. 3 is a detail perspective view of the co-acting clip members in disassembled relation to each other; Fig. 4 is a detail per-

spective view of the preferred form of toe member; and Fig. 5 is a detail perspective view of a modified form of toe member.

As shown in the accompanying drawings, and as best disclosed in detail in Fig. 1 55 thereof, the preferred embodiment of my toe calk includes a toe or wear plate 10 and a holder 11. The toe piece is formed from a single bar of metal, preferably steel, which is square in cross section and is provided on one longitudinal face with a centrally disposed longitudinal extension fin 12 which is adapted to be inserted in the holder. It will be noted that the fin is relatively thin, as compared to the member 11 60 and that the longitudinal edge portions of the adjacent face of this member constitute shoulders which are adapted to bear against the lower edges of the holder 11. This holder consists of a pair of co-acting clips 65 or jaws 13 and 14. The member 13 which is shown in detail in Fig. 3 includes a body portion 15 which is adapted to bear against the lower face of the shoe, an upstanding flange 16, and a pair of laterally extending 70 lips 17. The flange 16 is longitudinally curved and is adapted to bear against the curved edge of the portion of the shoe, while the lips 17 are adapted to bear upon the upper face of the shoe on opposite sides 75 of the tip 18 thereof. The terminals of the body plate 15 are provided with apertured lugs 19 through which screws 20 pass into the threaded bores 21 formed in the shoe. An aperture 22 is also formed in the body 80 plate 15 to receive the screw 23 which is threaded into a receiving bore formed in the shoe. Depending from the lower face of the body plate 15, is a socket plate 24 which is three-sided, being open in the rear. The 85 front wall of the socket plate is provided with three spaced apertures 25, 26 and 27.

The clip 14 includes a channel-shaped body portion 28 which is adapted to embrace the inner edge of the toe portion of 90 the shoe and a socket plate 29 which is adapted to close the rear side of the socket plate 24, as shown in Fig. 1.

When the toe piece 10 is to be attached to the shoe, the clip 13 is first applied 100

thereto in the manner shown in Fig. 2, the body plate 15 being disposed against the inner face of the shoe and the flange 16 against the outer edge thereof. The fin 12 of the toe piece is then inserted in the socket plate 24 and the socket plate 29 is applied. A pair of screws 30 and 31 are then passed through the openings 25 and 27, through the fin and into the threaded bores 32 and 33 of the plate 29. It will be seen that these screws serve not only to hold the fin within the socket formed by the members 24 and 29, but that they also serve to hold the channel-shaped body portion in proper engagement with the shoe. An additional screw 34 may be threaded through the bore 26 of the plate 24 into the central threaded bore 35 of the fin.

From the foregoing description and upon reference to the drawings, it will now be seen that the toe cork is of relatively simple design and that it is adapted for speedy application to or removal from the horse shoe. It will also be observed that the only changes necessary in the conventional horse-shoe is to provide the same with three threaded bores.

If desired, the modified form of toe piece shown in Fig. 5 may be substituted for the member 10. This modified toe piece consists in a rectangular plate of steel or similar metal which is provided with a centrally located threaded opening 36 and the terminally disposed apertures 37 and 38. The apertures 37 and 38 are adapted to receive the screws 30 and 31, while the threaded opening 36 is adapted to receive the screw 34. The lower edge of the modified toe piece is chamfered, producing a sharp cutting edge as shown in Fig. 5.

It is now to be noted that the holder, consisting of the two co-acting clips 13 and 14 may be employed with equal efficiency in holding either a toe piece of the type shown in Fig. 4 or of the type shown in Fig. 5. The first mentioned toe piece is designed for use, under ordinary conditions, while the second mentioned toe piece is adapted particularly for use on extremely slippery surfaces, as when a sheet of glass forms on a road or street, following a rain.

In reduction to practice, it has been found that the form of this invention illustrated in the drawings, and referred to in the above description as the preferred embodiment, is the most efficient and practical; yet realizing that the conditions concurrent with the adoption of this device will necessarily vary, it is desirable to emphasize the fact that various minor changes in the details of construction, proportion and arrangement of parts may be resorted to, when required, without sacrificing any of the advantages of

this invention, as defined by the appended claims.

65

What is claimed is:—

1. A toe cork for horse shoes including a pair of co-acting clips adapted to embrace the toe portion of a horse shoe, mating socket plates depending from the clips, a toe member having a fin inserted in the rectangular socket defined by the socket plates, and fastening devices passing through the socket plates and fin for securing the fin in position for connecting the socket plates.

70

2. A toe cork for horse shoes including a toe member and a holder for adjustably securing the toe member to the horse shoe, said holder including a pair of co-acting clip members, one of said clip members being adapted to embrace the outer edge of the shoe, the other of said clips being adapted to embrace the inner edge of said shoe, a substantially U-shaped socket plate depending from the first clip, and a straight socket plate depending from the second clip, said socket clips being adapted to mate, forming a rectangular socket adapted to receive the toe member, and fastening members passing through the socket plates and toe member for detachably securing the toe member thereto and for connecting the socket plates.

75

3. A toe cork for horse shoes including a pair of co-acting clips adapted to embrace the toe portion of a horse shoe, mating socket plates depending from the clips, one of said socket plates being substantially U-shaped and the other of said socket plates being flat and being disposed between the end walls of the U-shaped socket plate to define in connection therewith a substantially U-shaped socket, a fin inserted in the socket, and fastening devices passing through the socket plates and fin.

105

4. A toe cork for horse shoes including a pair of co-acting clips which embrace the toe portion of a horse shoe, a substantially U-shaped socket plate depending from that clip which embraces the forward edge of the shoe, a plane socket plate depending from that clip which embraces the rear edge of the toe portion of the shoe, said second socket plate being disposed between the side walls of the first mentioned socket plate, rearwardly extending lugs formed on the first mentioned clip, and fastening devices for securing said lugs to the shoe, the bottom portion of the second mentioned clip engaging at its terminals against said lugs, whereby it is held against transverse movement upon the shoe.

110

5. A toe cork for horse shoes including a pair of co-acting clips adapted to embrace the toe portion of the horse shoe, mating socket plates depending from the clips, said

115

120

125

plates defining a substantially rectangular socket, a toe member, a longitudinal fin rising from the toe member, said fin being disposed within said socket, the lower edges of the plates defining said socket being disposed to rest upon the upper face of the toe member, and fastening devices passing through a wall of the socket and into the fin

for securing the same against withdrawal from the socket.

In testimony whereof I hereunto affix my signature in the presence of two witnesses.

GEORGE ROBINS.
